UNITED STATES PATENT OFFICE.

THOMAS C. DAVIS, OF GREELEY, COLORADO.

PRESSURE-CONTROLLING MEANS FOR WRINGER ROLLS.

Application filed March 31, 1927. Serial No. 179,982.

This invention relates to pressure controlling means for wringer rolls.

With my improvements, which is also true as to prior arrangements, the wringer is adapted to be supported, upon the washing machine, in geared relation with the driving mechanism of the latter; but with former types of wringers the upper roll thereof is forced down, under relatively heavy pressure, towards the lower roll, by substantially stiff spring means disposed in the upper zone portion of the wringer, which pressure may not be facilely eased-up on or instantly relieved under certain emergency conditions.

It follows, therefore, that if there is an unyielding obstruction offered to the passage of the material between the rolls of the wringer, which might be caused by a compact lump in the material itself or any hard substance accidentally contained therein, a heavy shock or strain is imposed upon the apparatus and driving mechanism thereof, which stress would tend to impair its efficiency, if not actually disrupting or causing the breaking of parts thereof. More important still, it not infrequently happens that a portion of the garments or even a finger or hand of the operator becomes caught between the rolls, resulting in material injury, and such possibilities and actual occurrences are a great source of annoyance and fear to many users, because if a garment sleeve or hand of the operator became caught in the goods or between the rolls, it might not then be possible with the other hand to even have ready access to the switch control, for shutting off the power, and much less so for the manipulation of parts to relieve the pressure of the rolls.

One of the main objects of my improvements, therefore, has been to provide for quick-acting emergency release means, for instantly relieving substantially all pressure of the rolls, which means in a certain sense functions automatically, as it were, or semi-automatically under pedal control, as herein-after broadly and specifically set forth. Another primary object has been to provide for, at will and as desired during actual wringing operations, any degree of graduate or variable adjustment of the pressure of the rolls, by means of said pedal control, whereby thicker or thinner articles may be fed through between the rolls, under appropriately desired wringing pressure, without any other adjustment of parts, so that

the hands of the operator may at all necessary times be free to manipulate the articles or be otherwise employed.

The foregoing as well as other objects and advantages, however, will be more clearly apparent as incidental to the following disclosure, so that nothing would be gained by further enlargement upon the same initially. With these general outlining remarks, therefore, reference will now be had to the accompanying drawings, illustrating certain practical embodiments of the improvements, although susceptible to some variations without departing from the spirit of the invention, and in which drawings

Figure 1 is an isometric view that is partly in section and with one end standard of the wringer omitted, to more clearly disclose the improvements, the wringer being associated with a washing machine, fragmentarily illustrated, and the rolls of the wringer being substantially spaced apart, as when wringing heavy or thick articles, such as blankets, sweaters, or the like; Figure 2 is a local detail view in end elevation and looking in the direction of the arrow 2 of Figure 1; and Figure 3 is a local transverse sectional view taken along the line 3 of Figure 1.

Before actually describing the more essential features of the improvements, and for the purpose of more clearly understanding their functioning, it may not be amiss to first set forth the general combination of elements with which they are associated.

The numerals 5 and 6 designate respective casing walls of a washing machine, with which there is associated a detachably supported power operated wringer that is mounted in geared relation with the driving mechanism of the washing machine, as is well understood. There are also shown cross-bars 7, extending laterally of the wall 6, which have registering recesses 8, in their underneath faces, that function as guide-ways for a retractive actuating bar, herein-after referred to, and 9 indicates a retracting spring therefor, as interposed between the same and a part of the washing machine. It is obvious, however, that these exact details may be substituted for by other suitable and equivalently functioning means if desired.

10 indicates one of the end standards of the wringer framework, a similar end standard at the opposite end being omitted on

the drawings, which end standards may be suitably braced as by means of front and rear cross-bars 11, and 12 designates the top bar of the framework, which top bar preferably is bodily movable in a vertical direction. This top bar 12 is shown as being formed of channel metal, with a wooden filler, but this is not material.

The end standards 10 preferably are 10 low, to provide casings or housings for certain parts. Each of them may be conveniently formed of relatively stiff thin metal, after the fashion of rectangular-like open-ended tubing, with elongated slots 13 and 14 extending longitudinally of the upper and lower portions, respectively, of the inner wall thereof, leaving bearing webs or faces 15 and 16, at opposite sides of said slots, along said inner wall.

20 The end portions of the top bar 12, adjacently of the inner walls of said end standards 10, are each provided with a depending guide-head 17, which guide-heads are fixedly attached to said top bar 12 but are disposed in sliding relation with reference to the bearing faces or webs 15—16 of said standards. These guide-heads may also be of hollow formation, especially if they are to house intermeshing gears customarily carried by the shafts of the wringer rolls, and one of which gear wheels is indicated at 17^a. At any event, each of the guide-heads provides a longitudinal slot 18, for registration with a complementary one of the upper slots 13 of the end standards 10, and they may be of channeled formation as more clearly seen at Figure 3.

19 and 20 indicate any suitable journals or bearing blocks for the shaft ends 21 and 22 of the upper and lower wringer rolls 23 and 24, respectively, which rolls normally would be in approximate contact, but which are actually shown as substantially spaced apart, owing to the illustration of a relatively thick article 25 being fed through between the rolls. The said shaft ends, inwardly of their journal supports, extend through the slots 18 and 13, as is obvious, with all of said journals respectively housed within the hollow end standards 10, and the said upper journal elements 19 being so contained therein as to permit of their vertical play, hence a vertical play also of the upper roll 23, while the lower journal elements 20 are mounted in stationary relation. Any suitable supporting means may be provided, within the standards 10, for the stationary mounting of the lower journal bearings 20, such as a cross-web if desired, but I have simply illustrated such supporting means conventionally as embodying inwardly disposed lugs or projections 26. The right end of the lower shaft 22, shown broken off at Figure 3, extends through the outer wall of its end standard 10, and is associated with

the usual reverse control arrangement, of the wringer, that is mounted in gearing relation with the driving mechanism of the washing machine, as is fully understood.

In the further carrying out of my invention, from a broader aspect, the upper roll arrangement suspends relatively stiff spring means extending substantially below the position of the upper roll, which spring means is associated with tension regulating means therefor, preferably under pedal control, for applying thereto a downward force to establish and increase its tension as desired, or reversely to relieve said tension in part or in whole. Accordingly, when a downward force is imposed upon said spring means, the latter will become so substantially tensioned as to exert a strong downward pull on said upper roll, for supplying the normally desired working pressure, but at the same time allowing for a certain degree of resilient give or yielding vertical play of said upper roll, under the control or against the tension of said spring means. On the other hand, as soon as the downward force on said spring means is partly or wholly relieved, the downward pull on said upper roll will be correspondingly graduated or proportionally decreased, although the actual pressure of the upper roll, while there is any tension at all on the spring means, will in a measure be determined by the actual thickness of the article passing through between the rolls. At any event, if the spring tension is wholly relieved, it follows that the downward pressure of the upper roll will likewise be simultaneously relieved, and thus provide for the instantaneous emergency release hereinbefore referred to.

105 In the immediately preceding paragraph, I have stated perhaps the real gist of my invention in the broadest terms, because the main principles thereof may be embodied in various but equivalent combinations of elements. However, it is not believed to be expedient nor desirable, as it would serve no useful purpose, to fully set forth all such possible modifications, which are intended to be comprehended in my broader ensuing 110 claims, and accordingly I will now describe a practical arrangement which is preferred by me at the present time.

An elongated bar spring 27, shown as a flat plate spring, extends longitudinally 120 underneath the lower roll 24, in substantially spaced relation thereto, the ends of said spring being projected, through the slots 14, into the hollow end standards 10, and said spring ends being mounted by 125 hanger elements suspended from the supporting means of the upper roll 23. This may be most conveniently done, as shown, by means of closed loop yokes on hanger links 28—29 that freely encompass the lower 130

roll journals 20, but which are securely attached to the upper roll journals 19, as conventionally illustrated by bolt heads 30. The upper ends of said hanger elements are 5 preferably projected above said journals 19, so that these upper ends 31 may also be securely attached to the top bar 12, and the ends of the spring bar 27 are freely supported upon the lower cross-arms 32, of the 10 hanger elements, in a disconnected or limited sliding relation.

Means are provided to apply a downward force on the body of said bar spring 27, as desired by the operator, for causing its 15 downward bowing to give it appropriate tension, and reversely to relieve said downward force and the tension of said spring, which means is preferably pedal-controlled as hereinbefore suggested. Although equivalent 20 means, other than that actually shown, could be employed for this purpose, still in actual practice the following described means have been found very satisfactory.

A rock-shaft 33, extending contiguously 25 of one side of the bar spring 27, has its ends mounted by said bearing webs 15 of the end standards, or it may be mounted in any other suitable way. The shaft is provided with a presser finger or lug 34, adapted to engage and exert a downward pressure on 30 the body portion of said bar spring, and a reversely disposed actuating finger or lug 35, adapted to be engaged from its underneath side by an operating finger or lug 36 that is projected from the upper end of 35 a retractive vertically disposed actuating bar 37. The lugs 35 and 36 are disposed in entirely disconnected relation, that is to say the lug 35 is merely engaged by and rides 40 upon the lug 36 with a cam-like action. The actuating bar 37 would of itself be retractive, owing to gravitation, but to make its 45 action more positive and instantaneously responsive, as well as for retracting the pedal mechanism, the bar 37 is preferably made retractive by suitable resilient means, such as the normally closed coil spring 9 interposed between it and a lower part of the washing machine. The lower end of the 50 actuating bar 37 is provided with means, preferably antifriction means such as the roller 38, riding upon a cam 39 that is carried by a pedal shaft 40 which, through the medium of integral arms 41 or otherwise, 55 mounts an operating treadle base or pedal 42.

In operation, and under ordinary usage, the pedal 42 would be disposed relatively close to the floor, or say slightly tilted above 60 its horizontal position, so that with one foot resting on the pedal, or even with the heel on the floor and the ball of the foot on the pedal, it will be apparent that, by varying the foot pressure, the operator may facilely 65 regulate and control the pressure at the

wringer rolls, without any other adjusting means, for the appropriate wringing out of thicker or thinner articles, the operation being as follows.

Downward pressure on the pedal will 70 swing the cam 39 upwardly, or will tend to do so, for elevating the actuating bar 37 against the tension of its retracting spring 9. With this movement, as will be obvious, the presser lug 34 will bow the body portion 75 of the bar spring 27 downwardly, the ends thereof being disconnectedly or freely supported upon the lower portions of the hanger links for a limited sliding motion as before stated, which said downward bowing 80 of the bar spring will tension the latter to a degree proportionate to the foot pressure on the pedal, whereupon the tension of the bar spring 27 will cause a downward 85 pull on the hanger members 28-29, securely attached to the journals 19, for drawing the upper wringer roll 23 into closer pressing association with the lower one, under a relatively heavy but resiliently 90 yielding pressure. Reversely, the easing-up 95 of the pressure on the pedal 42 will correspondingly ease-up the pressure at the wringer rolls, and it follows that in the case of an emergency, such as heretofore referred to, a quick and entire release of foot pressure on the pedal 42 will result instantaneously in relieving all pressure at the wringer rolls.

If the upper ends of the hanger elements 100 28-29 are projected above the journals 19 and secured to the top bar 12, as actually shown and which is preferred, it will be noted that all of these elements, including the upper roll 23, will have conjoint vertical play. The upper roll and said top bar, 105 therefore, will always be maintained spaced the same distance apart, thus guarding against any binding therebetween, and more importantly guarding against the crushing of the fingers or hand of the operator if 110 accidentally inserted therebetween, when the upper roll is moved upwardly owing to the increased thickness of articles passing through between the rolls.

From all of the foregoing, it is believed 115 that the advantages and functioning of the improvements will be clearly apparent, but although I have thus set forth the same fully, in accordance with my present preferences, it will nevertheless be understood 120 that I do not wish to unnecessarily confine myself to all of the details exactly as disclosed, excepting as they may come within the terms or tenor of the ensuing claims, or equivalent elements and combinations thereof, or as fairly interpreted in the light of the specification if necessary.

What I do claim, as new and patentable, is:

1. In a wringer embodying an upper roll 130

- having supporting means for vertical play relatively to the lower roll, the combination of hanger elements depending from said supporting means, a bar spring freely mounted at its ends for limited sliding motions upon the lower ends of said hanger elements, and with said spring extending longitudinally below said lower roll, a lever, and means interposed between said lever and bar spring to respectively cause the downward bowing of said spring, for placing said spring under tension, and to relieve the downward bow thereof, upon the respective actuating and retractive movements of said lever.
2. In a wringer embodying an upper roll mounted by bearings for vertical play relatively to the lower roll, the combination of hanger links securely attached at their upper portions to the bearings of said upper roll and freely encompassing the bearings of the lower roll, a bar spring freely supported at its ends for limited sliding motions on the lower portions of said links, a pedal, and means interposed between said pedal and bar spring to exert a downward force on said spring, intermediate of its freely supported ends, upon downward pressure being imposed on said pedal, for placing said spring under downwardly bowed tension, and reversely relieving the tension of said spring upon the relieving of said pressure on said pedal.
3. In a wringer, the combination of hollow end standards, a vertically movable top bar therefor, a lower roll having its bearings housed within and in stationary relation to said standards, an upper roll having its bearing connected to said top bar and housed within said standards for vertical play therein, hanger links securely attached to the bearings of said upper roll and freely encompassing the bearings of the lower roll, a bar spring supported at its ends by said links, a rock shaft disposed contiguously of said spring and provided with an actuating lug and also with a presser lug adapted to bear down on the body portion of said spring, a retractive actuating bar for engaging said actuating lug to turn said rock shaft in one direction, for causing the downward bowing of said spring by said presser lug, a roller carried by the lower end of said actuating bar, and a pedal mounted on a shaft carrying a cam member, engaging said roller from underneath the latter, for positively operating said bar in its actuating direction and controlling its retractive movements by the foot pressure of the operator.
4. In a wringer embodying an upper roll mounted for vertical play relatively to the lower roll, the combination of a bar spring suspended at its ends from said upper roll and extending longitudinally below said lower roll, a rock-shaft disposed contiguously of said bar spring and provided with a presser lug operative upon said spring, and retractive lever-controlled means for actuating said rock-shaft in one direction to cause the downward bowing of said spring, by said presser lug, and thereby placing said spring under tension, while relieving said bowing and tension upon retractive movements thereof.
5. In a wringer embodying an upper roll mounted for vertical play relatively to the lower roll, the combination of a bar spring suspended at its ends from said upper roll and extending longitudinally below said lower roll, a rock shaft disposed contiguously of said bar spring and provided with an actuating lug at one position thereof and with a presser lug operative upon said spring, a retractive actuating bar for engaging said actuating lug to turn said rock shaft in one direction, for causing the downward bowing of said spring by said presser lug and thereby placing said spring under tension, while relieving said bowing and tension upon retractive movements thereof, and a pedal associated with said actuating bar for positively operating said bar in its actuating direction and controlling its retractive movements by the foot pressure of the operator.
6. In a wringer, the combination of hollow end standards, a vertically movable top bar therefor, a lower roll having its bearings housed within and in stationary relation to said standards, an upper roll having its bearing connected to said top bar and housed within said standards for vertical play therein, hanger links securely attached to the bearings of said upper roll and freely encompassing the bearings of the lower roll, a bar spring supported at its ends by said links, a rock shaft disposed contiguously of said spring and provided with an actuating lug and also with a presser lug adapted to bear down on the body portion of said spring, a retractive actuating bar for engaging said actuating lug to turn said rock shaft in one direction, for causing the downward bowing of said spring by said presser lug, a roller carried by the lower end of said actuating bar, and a pedal mounted on a shaft carrying a cam member, engaging said roller from underneath the latter, for positively operating said bar in its actuating direction and controlling its retractive movements by the foot pressure of the operator.

In testimony whereof, I affix my signature.

THOMAS C. DAVIS.
